A. FERNANDEZ.

SWITCH BOX.

APPLICATION FILED MAR. 1, 1918.

1,304,467.

Patented May 20, 1919.

UNITED STATES PATENT OFFICE.

ABEL FERNANDEZ, OF WASHINGTON, DISTRICT OF COLUMBIA.

SWITCH-BOX.

1,304,467.

Specification of Letters Patent. Patented May 20, 1919.

Application filed March 1, 1918. Serial No. 219,827.

To all whom it may concern:

Be it known that I, ABEL FERNANDEZ, a citizen of Mexico, residing at Washington, in the District of Columbia, have invented 5 certain new and useful Improvements in Switch-Boxes, of which the following is a specification.

This invention relates to improvements in switch boxes and it is the principal object of 10 the invention to provide a container for receiving an automatic cut-out, such as shown and claimed in my co-pending application bearing Serial Number 220,085 or any form of circuit closing means which will protect 15 the same and when closed, will serve to prevent tampering with the circuit closing means therein or the fraudulent opening of the box.

It is a more specific object of the invention 20 to provide the box with a novel form of means for retaining the cover or closure means thereover and for positively preventing the insertion of implements therewith or the fraudulent opening of the same.

25 The invention also aims to provide means for retaining the circuit closing elements in proper position upon the base thereof and as a consequence, insuring proper functioning of the same at all times.

30 In order that the invention and the manner of its application may be readily understood by those skilled in the art, I have in the accompanying illustrative drawings and in the detailed following description based 35 thereon, set forth a preferred embodiment of the invention.

In these drawings:

Figure 1 is a top plan view of the box base, the cover having been removed,

40 Fig. 2 is a vertical longitudinal section through the box having the cover applied.

Fig. 3 is a fragmentary detail in section taken on the line 3—3 of Fig. 1 with the cover applied showing the side connections,

45 Fig. 4 is a similar view taken on the line 4—4 of Fig. 1 showing the engagement of the box cover with the switch handle receiving element, and

50 Fig. 5 is a like view taken on the line 5—5 of Fig. 1 showing the engagement of the box cover with a portion of the segmental shoulder.

Having more particular reference to the drawings, in connection with which like reference characters designate corresponding parts throughout the several views, the im-

proved switch box includes a substantially oval base 1 formed preferably of porcelain or like insulating material having a plurality of openings 1' formed therein through 60 which screws or other similar fastening devices may be passed in order that the same may be secured to a suitable object. Formed upon the outer face of the base 1 at a point in proximity to the upper marginal portion 65 thereof is a segmental shoulder 3 having a channeled portion or lip 3' formed intermediate its ends and which as will be noted, has the upper marginal portion thereof beveled as at 4 for a purpose which will be 70 subsequently apparent. Curved brackets or keepers 5 are formed upon the opposite sides of the base 1 and have alined openings formed therein in order that other screws or like fastening devices 6 may be passed 75 through the same when necessary. A bracket or keeper 7 is also formed upon one end marginal portion of the base 1 and has alined openings 8 formed therein, whereby locking or sealing means may be engaged 80 with the same. In addition to forming the segmental channeled shoulder 3 upon the base, a segment 9 is also formed thereon adjacent the margin of the opposite base portion and has an opening formed therein, as 85 at 10, through which a switch handle may be passed.

In order that the base may be covered and the circuit closing means arranged thereon protected, a cover indicated in its entirety by 90 the numeral 11 is provided and comprises an oval concavo-convex body substantially conforming in shape and size to the base 1 and having a lateral inwardly extending curved lip 12 formed upon the inner side of 95 one end thereof engageable with the channeled portion 3' of the segmental shoulder 3, while an apertured tongue 13 is formed upon the remaining end of the same and is adapted to be arranged, at times, in the keeper 7. It is to be noted, that one portion of the cover is recessed as at 14 to permit the same to be engaged over the segment 9 while the adjacent end of the cover is formed with a shoulder 15 adapted to engage with the adjacent marginal portion of the keeper 7 when the tongue 13 is arranged therein. The cover 11 may be and preferably is formed of the same material from which the base 1 is constructed, although, it of course will be understood that any suitable material may be used, such as conditions or preference may

dictate. Apertured curved ears 16 are formed upon the side marginal portions of the cover 11 and are received in the keepers 5 when the cover is engaged over the base 1, 5 whereupon suitable fastening devices can be passed through the alined openings, thus preventing undue lateral movement of the cover with relation to said base.

In using my improved switch box, the elements constituting the circuit closing means are of course arranged upon and secured to the base 1 in a suitable manner. Since said base is secured to an immovable object by means of the screws or other fastening 15 means passing through the openings, lifting or other undue movement of the same will be prevented. With the circuit closing means thus positioned and connected, if desired, the cover 11 is arranged over the base 20 by sliding the same into engagement therewith, thus causing engagement of the lip 12 with the segmental channeled shoulder 3 and engagement of the tongue and the ears with their respective bracket portions. 25 With the cover thus positioned, the opening formed in the tongue and ears will be alined, thus permitting the insertion of the screws 6 through the keepers 5 and adjacent ears 16, while a wire tie 18 is passed through the 30 alined openings formed in the keeper 7 and the tongue 13 whereupon a seal 19 or other suitable fastening or locking means is engaged with the free ends thereof. In this connection, I desire to have it understood 35 that other forms of locking means may be employed, instead of the wire and seal herein shown and described; the object being to lock the cover in its closed position and to positively prevent tampering with the circuit closing means arranged in the box or 40 the fraudulent removal of the cover.

From the foregoing, it will be appreciated that I have provided an exceedingly effective and compact switch box, which will not 45 only serve as a positive guard for the circuit closing means arranged therein, but also will protect persons therefrom, since, the structure in its preferable form, is composed of insulating material. For this reason, the 50 box is rendered particularly desirable for use as a container for automatic cut-outs which are arranged by various power companies in dwellings or other buildings and serve as means for regulating the load, that 55 is, the amount of current conveyed into the dwelling; it being impossible to gain access to the cut-off for fraudulent purposes without detection.

It is to be also understood, that the box 60 may be used in the capacity of the ordinary junction box such as commonly used in arranging of electrical conduits, or the "wiring" of houses or other buildings.

As hereinbefore indicated, I do not wish to be understood as confining the invention 65 to the particular embodiment chosen for illustration herein, nor to the exact construction, arrangement and adoption of the parts shown and described, but I reserve the right to make any changes and alterations 70 that clearly fall within the spirit and scope of the invention.

I claim:

1. In a switch box, a base, a channeled segmental shoulder arranged on the base 75 adjacent one marginal portion thereof, a curved lip extending laterally from the cover engageable with the shoulder, and means engageable with the free ends of said base and cover for preventing relative movement of the same.

2. In a switch box, a base, a channeled segmental shoulder formed integral with one face of the base and arranged adjacent one marginal portion thereof, a cover, a laterally projecting lip formed complementally to said shoulder arranged on the cover and engageable with the shoulder, keepers formed integral with the opposite side marginal portions of said base, and ears formed 90 upon the opposite side marginal portions of said cover receivable in the keepers and adapted to receive securing means therethrough.

3. In a switch box, a base, a shoulder arranged on said base adjacent one marginal portion of the same, brackets arranged on the opposite side marginal portions of the base, a cover receivable over said base and engageable with said shoulder, ears formed 100 on the opposite side marginal portions of the cover receivable in said keepers, and means engaged with the free portions of said base and cover for preventing relative movement thereof.

4. In a switch box, a base, a channeled segmental shoulder formed integral with the base, keepers formed integral with the side marginal portions of said base, another keeper formed integral with the marginal portion of the base and arranged opposite to said shoulder, a cover, a curved laterally extending lip arranged upon the inner side of the cover receivable by the channeled shoulder, a tongue is formed upon the side marginal portions of the cover receivable in said keepers, and a tongue formed integral with one marginal portion of the cover arranged opposite to the curved lip receivable in the remaining keeper, said keeper, is, and 115 tongue, having alining openings therein for receiving fastening means therethrough.

In testimony whereof, I affix my signature hereto.

ABEL FERNANDEZ.
